J. PHILLIPS

THERMOMETER

Filed Sept. 3, 1926

INVENTOR
JOHN PHILLIPS
BY
Marshall & Hawley.
ATTORNEYS

UNITED STATES PATENT OFFICE.

JOHN PHILLIPS, OF WOODSIDE, NEW YORK.

DESIGN FOR A THERMOMETER.

Application filed September 3, 1926. Serial No. 18,967. Term of patent 3½ years.

To all whom it may concern:

Be it known that I, JOHN PHILLIPS, a citizen of the United States, residing at Woodside, county of Queens, and State of New York, United States of America, have invented a new, original, and ornamental Design for Thermometers, of which the following is a specification, reference being had

to the accompanying drawing, forming part hereof.

The figure is a perspective view of the article, showing my new design.

I claim:

The ornamental design for a thermometer, as shown.

JOHN PHILLIPS.
